[57] CLAIM

The ornamental design for a remote microphone or similar article, as shown and described.

DESCRIPTION

FIG. 1 is a top, front and left side perspective view of a remote microphone or similar article showing our new design;

FIG. 2 is a left side elevational view thereof, the right side being a mirror image with the omission of the push button;

FIG. 3 is a rear elevational view thereof; and

FIG. 4 is a bottom plan view thereof.
